TRANSPOSITION BRACKET

Rogers Case, Orange, N. J.; Ethel Case, executrix of the estate of said Rogers Case, deceased, assignor to Transandean Associates, Inc., Orange, N. J., a corporation of Delaware

Application June 21, 1951, Serial No. 232,737

4 Claims. (Cl. 174—33)

This invention relates to a bracket for transposing the paired wires of communication lines.

In modern communication systems it is general practice to transpose paired line wires at spaced intervals, to minimize noises on the lines and cross-talk. This transposition is of particular advantage in the so-called "phantom" and "carrier" circuits and in the carrier circuits exact spacing of the transposition points regardless of the spacing of the line poles is a matter of importance. In transposition brackets generally considered it is highly desirable that the spool-form insulators against which the wires are trained be rotatable, in order that the wires readily may be pulled to tightened relation on pole-mounted "point" brackets and that "span" brackets may be adjusted readily along the wires by which they are supported into a desired position between line poles. It is highly desirable that the pins on or with which the insulators rotate be supported adjacent both ends of the pins, as by mounting the pins and insulators in frames, or clevises. I have therefore previously invented and used transposition brackets of both the "point" and "span" types which provide a clevis mounting for rotatable insulators together with adequate structural strength enduringly to sustain the thrust of the wires.

It is an object of my present invention to provide a transposition bracket having rotatable clevis-mounted insulators and providing space within the bounds of the bracket for crossing the wires at different levels, which bracket while being of adequate strength is economical in the amount of metal included in its structure and lends itself to simplicity and economy in manufacture.

Another object of my invention is to provide a transposition bracket having the above-noted qualifications which is usable with but slight and obvious modification either as a span bracket or as a point bracket.

In the accompanying drawings illustrative of the embodiment of my invention:

Fig. I is a plan view of my transposition bracket, showing a pair of line wires transposed thereby.

Fig. II is a fragmentary end elevation showing the mounting of the insulators at one end of the bracket.

Fig. III is a vertical-sectional view taken in the plane of the section line III—III of Fig. I and looking in the same direction as in Fig. II.

Fig. IV is a side elevation of the bracket looking from the right in Fig. I.

Fig. V is a fragmentary plan view showing the adaptation of my transposition bracket for mounting on the cross-arm of a line pole as a "point" bracket.

With reference to the drawings, the primary supporting structure of the bracket is in the form of a cradle. The cradle comprises two base members 1 and 2 which are spaced from each other the desired width of the bracket and which provide mounting for the clevis forming members of the bracket structure. These base members 1 and 2 are connected by two arms 3 and 4 which are inclined convergently downward and are connected by a foot 5 which forms the lowermost portion of the bracket

proper. Desirably as shown, the cradle comprising the base members, convergent arms and foot is a one piece strap-form bar and desirably the base members 1 and 2 are plates which lie in a common horizontal plane.

5 Four clevises are formed for the rotatable mounting of four spool-form insulators in diagonally matching high and low pairs with respect to the base provided by the base plates 1 and 2. With respect to base plate 1 specifically considered and as shown particularly in Fig. II of the drawings, two strap-form bars 6 and 7 are secured to that member as by means of rivets 8. Each of bars 6 and 7 has the general contour of a flanged channel in side elevation comprising an intermediate region *a* for attachment to its base plate and two relatively flat offset regions *b* and *c* joined to intermediate region *a* by angularly extended legs *d* and *e* which are of unequal length. It will be noted that bars 6 and 7 are attached respectively at the upper and lower faces of the base plate and that they are in reversed relation with respect to the position of their longer legs *d* and shorter legs *e*. The result is to provide to one side of the base plate a higher clevis 9 the major proportion of which lies above the plane of the base and at the other side of the base plate a lower clevis 10 the major proportion of which lies below the plane of the base.

15 At the other end of the bracket, shown in Fig. III of the drawings, a second pair of similarly shaped bars 11 and 12 are similarly secured to base member 2 as by rivets 8. These bars 11 and 12 also comprise each an intermediate region *a* and two relatively flat regions *b* and *c* joined to the intermediate region of the bar by longer legs *d* and shorter legs *e* respectively. The bars 11 and 12, like the bars 6 and 7 lie at opposite faces of the base member to which they are secured with their longer and shorter legs oppositely arranged. This arrangement gives insulator-mounting clevises 13 and 14 between strap-form bars 11 and 12. Whereas at the end of the bracket shown in Fig. II the bars 6 and 7 are so arranged that the relation of their longer and shorter legs gives a high clevis 9 to the left in the drawing and low clevis 10 to the right in the drawings, at the end of the bracket shown in Fig. III the arrangement of the bars is such as to give an opposite arrangement of the clevises 13 and 14. Thus as shown in Fig. III, the low clevis 13 is to the left in the drawing and the high clevis 14 is to the right.

20 Taking the bracket as a whole, the relative arrangement of the bars 6 and 7 at one end of the bracket and the arrangement of the bars 11 and 12 at the opposite end of the bracket gives a diagonal matching of high insulator-mounting clevises 9 and 14 and low insulator mounting clevises 10 and 13. To equip the bracket frame for use as a complete bracket, four spool-form insulators 15, 16, 17 and 18 are mounted rotatably in the four clevises 9, 10, 13, and 14 respectively by means of insulator pins 19. It is to be understood that the insulators either may rotate on their pins 19, the pins may be rotatable in holes 20 in the regions *b* and *c* of the clevis-forming bars or both the pins and insulators may be rotatable with respect to each other and to the frame structure of the bracket. Returning to consideration of the general bracket assembly, the arrangement of the insulator-mounting clevises in the bracket frame causes the diagonal pair of insulators 15 and 18 to project chiefly above the base plane of the bracket and the insulators 16 and 17 to project chiefly below the base plane of the bracket.

25 The diagonally matched mounting of high and low wire-training insulators provides for the crossing of two line wires in vertically spaced relation. Room for the spaced crossing of the wires in their vertically spaced relation and within the bounds of the bracket is provided by the form of the bracket cradle, the arms 3 and 4 of which decline sharply from the base plane of the

bracket to the foot 5 of the cradle, so that the lowermost of the two wires is out of contact with the cradle structure. The use of the transposition bracket is shown in Fig. I of the drawings, in which one line wire A is trained on low insulators 16 and 17 and the other line wire B is trained on high insulators 15 and 18, with the wires crossed within the bounds of the bracket. As will be apparent, the position of the wires is such that they can be brought by relative lateral movement of the wires or the bracket into contact with the insulators within the bounds of the outwardly open clevises in which the insulators are mounted.

When the bracket is used as a span bracket, it is placed in such relation with the line wires in a region between the line poles that the wires are crossed within the bounds of the bracket and the bracket is suspended from the wires. In this relation of the bracket in the line, the rotatable mounting of the wire-training insulators provides for ready movement of the bracket into adjusted position along the line. In the suspended relation of the bracket with the line wires the cradle structure extends downwardly and functions as a balance to prevent swinging of the wires and possible inversion of the bracket under the weight of accumulated ice or trash.

The bracket cradle also provides for simple adaptation of the bracket for use as a point bracket to be mounted on the cross-arm of a line pole as in Fig. V of the drawings. To equip the bracket for such use it is necessary merely to secure attaching means such as attachment plate 21 to the foot 5 of the bracket cradle, as by rivets 22. Desirably holes 23 are preformed in foot 5 of the cradle for this purpose. In utilization of my transposition bracket as a point bracket, the rotatable mounting of the insulators facilitates the operation of drawing the line wires tight by a simple longitudinal pull at the pole where the bracket is installed.

It is possible and under some conditions desirable to cast the bracket frame in one piece of one of the "light" metals such as aluminum, magnesium and their alloys. In such case saving in the weight of included metal results from the form of the bracket frame. Particular advantages are obtained when using ferrous metal to fabricate the bracket frame as herein specifically shown and described. The cradle of the frame is a one-piece structure which can be made in a single die-pressing operation. The four strap-form bars which make the insulator-mounting clevises are identical and can be formed in a single die common to all of them. These facts give great manufacturing economy under all conditions and the identity in contour of the clevis-forming bars is of particular advantage. If in any installation of brackets it is desired to provide an altered vertical spacing of the wires crossed within the bounds of the bracket, it is necessary merely to provide one changed die to give an altered relation between the longer and shorter connecting legs *d* and *c* of all the clevis-forming bars.

The simplicity of the frame structure lends itself naturally to economy in the weight of metal included in the bracket frame. Whether it be fabricated as shown or made as a one-piece casting the form of the cradle increases the utility of the bracket frame. The downward convergence of the cradle legs with interconnection at the lower end of the legs gives the effect of a cantilever and greatly increases the resistance of the frame to torsional stresses caused by the thrust of the wires. This is one contributing factor to economy in the weight of metal included in the bracket frame.

As used herein the terms "horizontal," "lowermost," "downward," "end," "side" and the like refer to what may be considered the normal position of the bracket in a line the wires of which are transposed by the bracket in accordance with preexisting general practice.

Having disclosed one embodiment of my invention, it is to be understood that changes in material, structure and arrangement may be made within the bounds of the in-

vention as defined in the statement of the claims appended hereto.

I claim as my invention:

1. A transposition bracket for paired line wires the frame structure of which comprises a central cradle having two arms of approximately equal length downwardly convergent and interconnected at their lower ends and two relatively spaced base members on said arms in a common horizontal plane, two bars secured on opposite faces of each of said base members, said two bars associated with each of the said base members having at both ends thereof offset regions at different levels with respect to the base member, the offset regions of the two said bars being superposed and spaced vertically from each other to provide two outwardly open insulator-mounting clevises extending one chiefly below and the other chiefly above the horizontal plane of the said associated base member, the relative arrangement of the said clevises-forming bars being reversed at the two said horizontally spaced base members of the bracket to give a diagonal matching of higher and lower clevises, and spool form insulators rotatably mounted in the said four clevises of the bracket for crossing of the two line wires at different levels within the cradle of the bracket.
2. A frame structure for a transposition bracket for paired line wires comprising a central cradle having two arms of approximately equal length downwardly convergent and interconnected at their lower ends and two relatively spaced base members on said arms in a common horizontal plane, two bars on opposite faces of each of said base members, said two bars associated with each of the said base members each having at both ends thereof offset regions at different levels with respect to the base member, the offset regions of the two said bars being superposed and spaced vertically from each other to provide two outwardly open insulator-mounting clevises one extended chiefly below and the other chiefly above the horizontal plane of the said associated base member, the relative arrangement of the said clevises-forming bars being reversed at the two said horizontally spaced base members of the bracket to give a diagonal matching of higher and lower clevises.
3. A frame structure for a transposition bracket for paired line wires comprising a single central cradle having two downwardly convergent arms of approximately equal length and an interconnecting foot at the lower ends of said arms, and two insulator-mounting structures on the upper ends of the said arms of the cradle, the said insulator-mounting structures each being extended in opposite horizontal directions from its associated arm of the cradle and each being forked at both its ends to provide two outwardly open insulator-mounting clevises, the said two clevises of each insulator-mounting structure being at different levels with respect to the foot of the said cradle and the four clevises provided by the two insulator-mounting structures being oppositely arranged on the two said arms with respect to the said higher and lower levels of the clevises, to give a diagonal matching of the higher and lower insulator-mounting clevises in the structure of the frame.
4. A transposition bracket for paired line wires the frame structure of which comprises a single central cradle having two downwardly convergent arms of approximately equal length and an interconnecting foot at the lower ends of said arms, two insulator-mounting structures on the upper ends of the said arms of the cradle, the said insulator-mounting structures each being extended in opposite horizontal directions from its associated arm of the cradle and each being forked at both its ends to provide two insulator-mounting clevises, the said two clevises of each insulator-mounting structure being at different levels with respect to the foot of the said cradle and the four clevises provided by the two insulator-mounting structures being oppositely arranged on the two said arms with respect to the said higher and lower

levels of the clevises, to give a diagonal matching of the higher and lower insulator-mounting clevises in the structure of the frame, and spool form insulators rotatably mounted in the said four clevises in the bracket for crossing of the two line wires at different levels within the 5 cradle of the bracket.
